UNITED STATES PATENT OFFICE.

WALTER SMITHERS, OF BROOKLYN, NEW YORK.

SCAFFOLD HORSE.

Application filed September 23, 1921. Serial No. 502,821.

To all whom it may concern:

Be it known that I, WALTER SMITHERS, a citizen of the United States, and a resident of Brooklyn, in the county of Kings and 5 State of New York, have invented certain new and useful Improvements in Scaffold Horses, of which the following is a specification.

My invention relates to those devices used 10 during building, painting or similar operations and known as scaffold horses and by means of which, in conjunction with planks or boards, a scaffolding of the desired height may be expeditiously erected in a well 15 known manner to enable the workman to operate on a part normally beyond his reach.

The object of the invention is the production of a scaffold horse of substantial 20 strength and rigidity which shall be simple in construction and cheap to manufacture and which shall be, by preference, of the knockdown type, thereby making for economy of space when not in use and corresponding cheapness in storage or shipping.

Other objects and advantages of the invention will appear from the accompanying description, the invention consisting in the novel parts and combinations thereof 30 hereinafter more particularly described and then specified in the claims.

In the accompanying drawing showing a practical embodiment of the invention:

Fig. 1 is a front elevation of my improved 35 scaffold horse.

Fig. 2 is an end view thereof.

Fig. 3 is a vertical cross-section on the line 3—3 of Fig. 1.

Fig. 4 is a side elevation of a portion 40 of the body or top of the device adjacent one end thereof.

Fig. 5 is a vertical cross-section on the line 5—5 of Fig. 2.

Figs. 6 and 7 are detail views of portions 45 of the device.

Referring in detail to the several figures of the drawing:

1 indicates one pair of the supporting legs for the device while 2 indicates the other 50 pair thereof. The legs of each pair extend diagonally upwardly with a space obtaining intermediate the upper ends as illustrated, said spaces being of a width sufficient to snugly receive the body or top 3 of the device, said body or top comprising a rectangular-shaped board or beam. The legs of 55

each pair are secured together by outer metallic cross plates 4 attached to the outer edges of the legs and by inner metallic plates 5 attached to the inner edges of said 60 legs, said plates being screwed or otherwise fastened to said edges by suitable nails, bolts or screws. All of said plates are provided with squared indentations or notches 6 adapted to slidably and snugly receive the 65 body or top 3.

The body or top 3 is provided on its bottom adjacent either end thereof with a slot 7 which slots receive the edges of the inner plates 5 at the points where the 70 notches 6 in said inner plates are located thus providing a detachable interlocking of said inner plates and body or top. Said inner plates 5 lie in a higher horizontal plane than the outer plates 4 as shown 75 which by being disposed in different horizontal planes by widening the bracing action vertically and cause the strains to which the device is subjected to be more fully distributed therethrough and consequently increases the strength. Also the body or top 80 3 when in position intermediate the ends of the legs is fully received by all the indentations or notches 6 in both the inner and outer plates for the reason that the side 85 walls of the notches 7 straddle the inner plates 5 at their indented points as illustrated. The body or top 3 may be expeditiously and removably placed in proper position and when in position it is incapable of 90 movement in any direction except an upward one and it may be detachably locked against an upward movement in the manner to be presently described.

8 indicates supporting bars comprising 95 angle-irons the outer ends of which are flattened as at 9 and are secured to the outer edges of each pair of legs 1 and 2 by suitable screws or bolts or analogous fastening means. Each of said supporting 100 bars is provided in the lower wall thereof with an open slot 10. The body or top 3 has secured thereto in any desirable manner and preferably equidistant from the ends thereof metallic supports 11 the ends of 105 which are perforated and which receive the hooked ends of supporting rods 12, whereby said rods are loosely but preferably non-detachably suspended from said supports 11. Said rods 12 are provided with screw-threaded ends 13 extending through and 110 loosely carrying reinforcing angle-pieces 13'

which are slidable thereon and the sides of which are adapted to engage the sides of the supporting bars 8 with which they interfit. To detachably fasten the supporting rods 12 to the bars 8, the ends of the rods are slipped within the slots 10 and the sides of the angle-pieces 13' are brought into engagement with the corresponding sides of the bars 8 and the parts held in position by 10 means of winged nuts 14 screwed on the ends 13 of said rods and bearing against said angle-pieces. The angle-pieces 13' being interlocked by one angle with the side of the bar 8 opposite the slot not only act to 15 effectively prevent the rods 12 from slipping out of the slots 10 but act as additional strengthening and supporting members for the parts.

15 indicates longitudinal supporting members comprising angle-irons which are pivotally secured at one end as by the pivots 16 to the front faces of each of the legs 1 while the other ends thereof are provided with L-slots 17 receiving pins 18 secured in the 20 legs 2 whereby said pins will be drawn within said L-slots to detachably and automatically lock the members 15 to the legs 2 when the pairs of legs 1 and 2 are drawn towards each other by operation of the winged nuts 25 14 in the manner previously described. If so desired the pins 18 may be screw-threaded and may have screwed thereon winged nuts 19 which serve as additional locking or holding means for the parts.

35 It will be obvious from the above explained construction that the body or top 3 is incapable of a vertical movement by the action of the rods 12 when the parts are set up and attached together and the device is 40 ready for use and that it is incapable of a longitudinal or transverse movement due to its interlocking with the inner plates 5 and its supported position intermediate the ends of the legs. It will also be apparent 45 that the pairs of legs 1 and 2 are prevented from rocking or swaying laterally or collapsing by means of the rigid members 15 which detachably hold them together, the top wall of said members 15 also providing 50 a horizontal step or support which may be mounted when so desired.

The construction of device described makes an exceedingly strong and substantial scaffold horse capable of severe strains and 55 stresses without danger of collapsing or breakage. When not in use the parts may be disassembled and shipped or stored in three pieces to wit: two pairs of legs one of which carries the members 15 and the 60 top or body 3 which carries the rods 12 which may be swung inwardly on the supports 11 and longitudinally of the top or body 3 in an obvious manner.

What I claim as my invention is:

65 1. A scaffold horse comprising two pairs

of legs with a free space between the upper ends of the members of each pair, crossing plates connecting said members at their outer and inner edges and disposed in different horizontal planes and a detachable body fitting between and engaged by the upper ends of said pairs, said body and the edges of said plates having respectively notches for establishing interlocking engagement between said body and said plates. 75

2. A scaffold horse comprising two pairs of legs each pair being spaced apart adjacent their upper ends, cross-plates in pairs attached respectively at their ends to the inside and outside of, and rigidly connecting together each pair of legs, a body removably engaging the upper ends of said legs and notched to interlock with said plates, supporting bars secured to each pair of legs below said plates, rods secured to said body and detachably engaging said bars and longitudinal supporting members detachably fastening the pairs of legs together. 80

3. A scaffold horse comprising two pairs of legs extending diagonally upwardly with a space obtaining intermediate the extreme free ends of each pair, plates fastened at both ends and rigidly connecting together each pair of legs and provided with indentations therein, a body removably fitting within the space between the legs and also fitting within and resting in the bottom of said indentations and provided with notches on its bottom receiving said plates, supporting bars secured to the edges of each pair of legs, rods swingingly secured to said body and detachably secured to said supporting bars, and supporting members comprising angle-bars pivoted to the front sides of two of said legs and detachably secured to the front sides of the other two legs. 95

4. A scaffold horse comprising two pairs of legs, a body engaging said pairs, supporting bars comprising angle irons connecting the legs of each pair and each provided with a slot in one face thereof, rods secured to said body and adapted to enter said slots and angle-shaped means carried by said rods and adapted to engage said supporting bars and to lock the rods against disengagement from the slots. 100

5. A scaffold horse comprising two pairs of legs, a body connecting the pairs, supporting bars connecting the legs of each pair and each provided with a slot, rods pivotally secured to the body, angle pieces through which the ends of the rods pass and clamping nuts screwed to the ends of the rods and bearing against said angle piece. 110

6. A scaffold horse comprising two pairs of legs, a body engaging said pairs, supporting bars connecting the legs of each pair and each provided with a slot therein, rods secured to said body and adapted to enter said slots, said rods having threaded 115 120 125 130

ends, means carried by said rods and adapted to engage said supporting bars on the side thereof opposite the slot, and clamping nuts engaging the threaded ends of the rods for drawing the parts together.

7. A scaffold horse comprising two pairs of legs, a body engaging said pairs, bars connecting the legs of each pair, rods secured to said body and each provided with threaded ends adapted to engage the said bars respectively, longitudinal supporting members pivotally secured to one pair at one

end and provided with L slots at their other end receiving pins on the other pair and nuts engaging the rods to draw the pairs together and thereby lock the slotted ends of the supporting members to the pins. 15

Signed at New York, in the county of New York and State of New York, this 21st day of September, A. D. 1921.

WALTER SMITHERS.
